UNITED STATES PATENT OFFICE.

SYLVESTER P. DENISON, OF BROOKLYN, NEW YORK, ASSIGNOR TO GEORGE R. THOMPSON, OF PHILADELPHIA, PENNSYLVANIA.

APPARATUS FOR CUTTING ELECTRICAL CONDUIT-PIPES.

SPECIFICATION forming part of Letters Patent No. 431,564, dated July 8, 1890.

Application filed August 10, 1889. Serial No. 320,355. (No model.)

To all whom it may concern:

Be it known that I, SYLVESTER P. DENISON, of Brooklyn, county of Kings, and State of New York, have invented an Improved Apparatus for Cutting Electrical Conduit-Pipes, 5 of which the following is a specification.

The object of my invention is to provide an apparatus for making longitudinal cuts in a continuous pipe. It is designed more especially to be used in connection with another apparatus, upon which I have filed application for Letters Patent, for making circular or transverse cuts in a continuous pipe, the use of both apparatus enabling me to cut a 15 section from a continuous pipe without injuring or disturbing anything lying therein—such, for instance, as a cable of electrical conductors with which lateral or house connections are to be made. The apparatus is, 20 however, not limited to any special application.

The subject-matter claimed is hereinafter specified.

In the accompanying drawings, Figure 1 is 25 a side elevation of the apparatus applied to a section of a pipe; Fig. 2, an end view of the same, and Fig. 3 a transverse section on the line 3 3 of Fig. 1.

A represents the section of pipe. The cutter-frame consists of a longitudinal bar B, having at each end and at right angles thereto cheek-pieces B', formed with curved faces fitting the side of the pipe. This frame is clamped against the pipe by two yokes C, each 35 having a curved end C', embracing the side of the pipe opposite to that on which pieces B' bear, and an opposite end C², extending outside of the cheek-piece B'. A screw clamping-bolt c in the end C² works against the outer 40 side of the cheek-piece and serves to clamp the cutter-frame firmly to the pipe. A screw feed-shaft D has its bearings in the two cheek-pieces B', and between the latter carries a correspondingly-threaded traveling cutter-block E, which may be moved back and forth 45 by the rotation of the screw-shaft. A cutter-head F, sliding transversely to the screw-shaft in the socket or ways in the block E, is adjusted at right angles to the axis of the pipe 50 by means of a screw-bolt f, working at right angles to the axis of the pipe in a flange e on

the head E, and also in the end of the cutter-head F. The opposite end of the cutter-head has a sleeve F' at right angles thereto, and in this sleeve a cutter-shaft G has its bearings. On the end of the shaft extending over the pipe is a toothed-cutting-wheel g, and at its opposite end g' the shaft is squared to receive a key or crank for rotating it.

X indicates a cable of electrical conductors 60 lying in the pipe. The cutter-frame B B' having been clamped to the pipe, the cutter g may, by means of the adjusting-bolt f, be drawn down against the pipe. The cutter may then be rotated by a key or crank applied to the end g' of the cutter-shaft and advanced as required by turning the feed-shaft D. In its movement back and forth the side of the block E merely bears against the face of the bar B.

The details of construction may be varied without departing from the invention; but the construction shown is that which I prefer.

I claim as my invention—

1. The combination, substantially as set 75 forth, of the cutter-frame adapted to be applied to the side of a pipe, securing devices for holding it in place, a longitudinally-traveling block E, a cutter-head F, adjustable in guides in the traveling block E, and a cutter 80 G, having its bearings in said adjustable cutter-head.

2. The combination, substantially as set 85 forth, of the cutter-frame adapted to be applied to the side of a pipe, securing devices for holding it in place, the traveling block E, a screw-shaft extending therethrough for moving it longitudinally, a cutter-head F, having a sleeve-bearing F', devices for adjusting the cutter-head in guides formed in the traveling block E, and a cutter journaled in the sleeve F'.

3. The combination, substantially as set 95 forth, of the cutter-frame adapted to be applied to the side of a pipe, securing devices for holding it in place, a longitudinally-traveling cutter adjustable transversely to the pipe and carried by the cutter-frame, and means for rotating the cutter without moving it longitudinally relatively to the pipe.

4. The combination, substantially as set 100 forth, of the cutter-frame, the cheek-pieces

interposed between the frame and the pipe, clamps for securing the frame to the sides of the pipe and adjusting the cheek-pieces, a feed-shaft having its bearings in the cheek-pieces, a traveling cutter-block operated by the feed-shaft, a cutter-head carried by the cutter-block and adjustable transversely to the feed-shaft and pipe, a rotating cutter-shaft carried in bearings in the cutter-head, 10 and a cutter carried by said shaft.

5. The combination, substantially as set forth, of the yoke-frame, cheek-pieces interposed between the yoke-frame and the pipe, devices for adjusting the cheek-pieces relatively to the pipe, the cutter-block, the cutter mounted therein, a feed-shaft, and gearing between the cutter and the feed-shaft.

15. The combination, substantially as set forth, of the frame, cheek-pieces interposed between the frame and the pipe, devices for adjusting the cheek-pieces, the cutter-block,

a screw-shaft extending through the cutter-block and having bearings in the cheek-pieces, the cutter, and means for adjusting it transversely to the screw-shaft.

25. 7. The combination, substantially as set forth, of the cutter-frame consisting of the longitudinal bar B and the curved cheek-pieces B', the clamping-yokes, the screw-threaded feed-shaft having its bearing in the 30 cheek-pieces B', the longitudinally-traveling block E, the cutter-head sliding in ways in said block transversely to the feed-shaft, a screw-bolt for adjusting the cutter-head, and a cutter carried by said head and adapted to 35 make a longitudinal cut in the wall of a pipe.

In testimony whereof I have hereunto subscribed my name.

SYLVESTER P. DENISON.
